UNITED STATES PATENT OFFICE.

FRANCIS P. McCOLL, OF ST. ANDREWS, NEW BRUNSWICK, CANADA, ASSIGNOR TO AMERICAN KEY CAN COMPANY, OF CHICAGO, ILLINOIS, A CORPORATION OF NEW JERSEY.

PACKING DEVICE.

1,171,967.

Specification of Letters Patent. Patented Feb. 15, 1916.

Application filed April 9, 1913. Serial No. 760,078.

To all whom it may concern:

Be it known that I, FRANCIS P. McCOLL, a subject of the King of England, residing at St. Andrews, county of Charlotte, Province of New Brunswick, Dominion of Canada, have invented a certain new and useful Improvement in Packing Devices, and declare the following to be a full, clear, and exact description of the same, such as will enable others skilled in the art to which it pertains to make and use the same, reference being had to the accompanying drawings, which form a part of this specification.

One of the commonest forms of receptacle for sardines and other commodities is the roll top can having one head soldered to the can body in such a way that it may be removed by rolling it up on a key, the other head being joined to the can body by a double seam. It is usual to apply the roll top first and to add the other head after the can has been filled. Consequently at the time the can is being filled the head which in the completed package is the top serves as the bottom and the first layer or quantity of goods packed in the can lies upon this head and is thereafter concealed from the sight of the packer as additional layers or quantities of goods are introduced. The packer is therefore unable to be certain that the first layer or quantity placed in the receptacle, and which is the top layer when the receptacle is opened, will present the neatest possible appearance because it may have been disturbed during the completing of the packing.

My invention has for one of its objects to produce a simple and novel device for packing receptacles in such a way that the last layer or quantity of goods packed by the operator, and which may therefore be arranged neatly, will form the bottom layer in the receptacle to be filled and consequently will be the top layer when the roll top or head is removed.

While my invention is particularly adapted for filling or packing roll top cans or receptacles of the kind heretofore specified, it is not limited to this use alone because it may be advantageously employed for packing receptacles of various kinds, particularly those which are deep as compared with their widths; therefore in one of its aspects my invention may be said to have for its object to produce a simple and novel

device which will make the packing of goods in layers in receptacles of various kinds simple and easy.

The various features of novelty whereby my invention is characterized will herein-after be pointed out with particularity in the claim; but, for a full understanding of my invention and of its objects and advantages, reference may be had to the following detailed description taken in connection with the accompanying drawing, wherein:

Figure 1 is a top plan of an embodiment of my invention designed for packing rectangular cans such as sardine cans; Fig. 2 is an end view of the device shown in Fig. 1; Fig. 3 is a section on line 3—3 of Fig. 1; Fig. 4 is a view similar to Fig. 3 illustrating the first step in the transfer of the goods from the packing device to the final container; Fig. 5 is a view similar to Fig. 4, illustrating the second step in transferring the goods to the container.

Referring to Figs. 1 to 5 of the drawing, 1 represents an open-ended tubular member conforming in shape to the cross section of a receptacle to be filled and having a depth preferably greater than the depth of the receptacle. In the arrangement shown, the member 1 is made substantially rectangular so as to fit into an open sardine can, but it will of course be understood that the shape of the receptacle to be filled is immaterial since the member 1 may be given any shape required to adapt it to any particular can or other receptacle. The member 1 is preferably made of thin material such as tin or other suitable sheet metal and within the same is a movable transverse partition or bottom, 2, shaped to conform to the interior of the member 1 and slideable up and down therein. In the particular arrangement shown, the height of the member 1 is made approximately equal to the depth of a can to be filled plus the thickness of the movable bottom, so that when the movable bottom is at the lower end of the member there is above it a chamber having substantially the same size and shape as the interior of the can to be filled.

With the parts in the positions indicated in Fig. 2 the chamber within the member 1 and lying above the movable bottom may be packed with the fish or other commodity just as the cans themselves are ordinarily packed, care being taken that the upper

most layer is neatly arranged. A can to be filled is now slipped down over the filled packer as indicated at 3 in Fig. 4, the uppermost layers of goods in the packer being in contact with the bottom of the can. The can and the packing devices are then turned upside down as a single unit so that the can is on the under side as indicated in Fig. 5. With the parts in this position, the packing device may be removed from the can, leaving the goods in the can in an undisturbed condition. This may be accomplished by grasping the projecting portion of the tubular member and lifting it while the movable bottom is held down with one or more of the fingers of the hand in which the tubular member is held. This causes the tubular member to rise up out of the can, leaving the can filled with the goods previously contained in the packing device, as indicated in Fig. 5. The movable bottom is now at the opposite end of the tubular member from that at which it was located before the transfer of the packed goods to the can was made and above it is a chamber ready to be filled; so that it is unnecessary to reverse the packing device after it is removed from the can in order to place it in condition to receive a new charge.

It will be seen that the layer of goods which was the top layer in the packing device, is, after the transfer, the bottom layer in the can. Consequently where the can is of the roll top type of which the roll top is the bottom head at the time the can is being filled and the top head at the time the can is opened, the can when opened after having been packed in the manner described, has on top the layer last to be packed and which it was possible to arrange carefully; and therefore when the can is opened the contents will present a neat and attractive appearance.

If desired, the movable bottom may be suitably interlocked with the tubular member so as to prevent accidental separation between the same. One way in which this may be accomplished is to provide the movable bottom with a projecting pin or pins, 4, at one or both ends, the pin or each of

the pins, where there is more than one, extending into a suitable slot, 5, cut into or through the wall of the tubular member. In the arrangement shown, there are two of these slots and each is made just long enough to limit the movement of the bottom member in one direction or the other, when the bottom member has gone far enough to form with the tubular member a chamber of substantially the same depth as the can to be filled. In this arrangement, therefore, the interlocking of the two members of the packing device together serves both to prevent accidental disengagement and also automatically to form in the packing device a measured chamber at one end or the other, depending upon the end of the tubular member in which the bottom happens to be.

While I have illustrated and described only a single embodiment of my invention, I do not desire to be limited to the exact structural details thus illustrated and described; but intend to cover all forms and arrangements which fall within the terms employed in the definitions of my invention constituting the appended claim.

I claim:

A packing device for sardine cans comprising a container open at both ends and conforming in cross section to the shape of a sardine can, a transverse partition or bottom mounted in said container so as to be movable lengthwise thereof, and interlocking means between the container and the partition or bottom constructed and arranged to permit the partition or bottom to be moved from one end of the container toward the other and be held against separation from the container, and the depth or length of the container being equal to the depth of the can to be filled plus the thickness of said bottom or partition.

In testimony whereof, I sign this specification in the presence of two witnesses.

FRANCIS P. McCOLL.
